H. MAIBAUER

CLOCK

Filed May 26, 1924

INVENTOR.
Herman Maibauer
BY
Thomas Donnelly
ATTORNEY.

UNITED STATES PATENT OFFICE.

HERMAN MAIBAUER, OF DETROIT, MICHIGAN.

CLOCK.

Application filed May 26, 1924. Serial No. 715,891.

To all whom it may concern:

Be it known that I, HERMAN MAIBAUER, a citizen of the United States, residing at Detroit, in the county of Wayne and State 5 of Michigan, have invented a new and useful Improvement in a Clock, of which the following is a specification.

My invention relates to a new and useful improvement in a clock and is particularly 10 adapted for use with alarm clocks. In the use of alarm clocks it has been found that the alarm bell, after having been used for a short time, becomes ineffective in arousing the sleeper inasmuch as the auditory nerves 15 of the sleeper become accustomed to the sound. In order to provide an alarm clock in which the sound may be varied from time to time so that the sleeper will not become accustomed to the particular sound of the 20 alarm is an object of the present invention.

Another object of the present invention is to provide an alarm clock having a plurality of alarm sounding members which may be operated in conjunction with each 25 other or which may be operated singly, the tone or sound of the different alarm members being different so as to produce a different effect upon the sense of hearing.

Another object of the invention is the 30 provision in an alarm clock of a plurality of alarm members adapted for operation by a striking member, and so mounted as to be adjustable relatively to the striking member so as to produce in the various positions 35 of adjustment a different sound or tone depending upon the point of contact of the striking member with the alarm member.

Another object of the invention is the 40 provision of an alarm clock having a plurality of alarm members and means for carrying the same, the structure of which will be simple, economical and durable.

Other objects will appear hereinafter.

The invention consists in the combinations 45 and arrangements of parts hereinafter described and claimed.

The invention will be best understood from a reference to the accompanying drawings which form a part of this specification 50 and in which,

Fig. 1 is a front elevational view of the invention,

Fig. 2 is a side elevational view of the invention,

Fig. 3 is a bottom plan view of the invention,

Fig. 4 is an enlarged fragmentary side elevational view of one of the supporting legs,

Fig. 5 is a fragmentary front elevational view of a modified form of the invention,

Fig. 6 is a fragmentary top plan view of the supporting bar and sounding member shown in Fig. 5.

The invention, in its preferred form, comprises an alarm clock 9 of the conventional structure having an alarm operating stem 10 projecting therefrom and provided with a striking head 11. Mounted on opposite sides of the casing of the clock 9 are a pair 65 of arcuate legs 12 and 12', suitable rivets being projected through the ends of the legs and through the casing of the clock for securing the ends in operative relation thereto. As shown in Fig. 1, the ends of the legs 12 70 and 12' are cut arcuately as at 13 and 13' respectively, so as to lie in contact with the periphery of the clock, the extreme ends of the legs at this arcuate cut being very thin 75 so as to taper off gradually to the periphery of the clock casing. The free ends of the legs 12 and 12' are provided with tongues 14, 15 and 16, which are folded upon the main body of the legs so as to embrace a strip 17 of rubber having a pair of tongues 18 and 19 80 which project outwardly from the ends of the legs intermediate the tongues 14, 15 and 16, so as to form a soft, yielding, contacting 85 surface with which the legs engage against the supporting member upon which it is placed.

An alarm supporting bar 20 connects the legs adjacent their free ends, the connection of the ends of the supporting bar 20 with the ends being made in any desirable manner; such as, riveting or projecting integral tongues from the supporting member through slots formed in the legs. The supporting member is provided with a pair of elongated slots 21 and 22. It will be noted in Fig. 1, that these slots are not 100

positioned the same distance from the striker 11. The slot 22 is positioned a greater distance from the striker 11 than is the slot 21. Projected through the slot 22 5 is a bell stem 23 upon which is fixedly mounted a collar 24, the free end of the bell stem 23 being threaded to accommodate a wing nut 24, the opposite end of said stem being fixedly mounted in a bell or alarm 10 member 25.

Projected through the slot 21 is a bell stem 26 having a collar 26' fixedly mounted thereon and threaded at its free end to accommodate a wing nut 24', the opposite end 15 of said bell stem being fixedly mounted on a bell or alarm sounding member 27. It will be noted that the bell 25 is of larger dimensions than the bell 27. By forming these 20 out of the same material and arranging them in different sizes, as shown in the drawing, it is apparent to those skilled in the art, that a striking of the bells will give off a different tone. In operation when the 25 striking arm is brought into contact with the bells, an alternate sounding of each will be had commingled with the alternate sounding of the other, to produce a discordant or harmonious sound depending upon whether the bells are in harmony or not. By adjusting 30 the bells relatively to the striker and permitting the striker to strike the bell near the lip or near the base will cause the bell to give off a different tone, or at least give off notes of different intensity. In this way 35 the bells may be so adjusted as to vary the sound which is given off upon a ringing of the alarm so that the sleeper may be roused by a new combination of sounds.

By removing one of the bells entirely, the 40 clock may be used as an alarm clock ringing only one of the bells. After the sleeper has become accustomed by repeated ringing of the bells on different days to the sound set forth by the same bell, the bell may be 45 changed and a new one substituted therefor. The new bell may be of different material or of different size, as desired, the different materials giving off different notes when formed into bells of the same size. In 50 the construction of the device the applicant prefers to employ brass bells as the tone given off is a clear and distinct one. However, the material of which the bells may be made is optional with the one constructing 55 the same. If desired, chimes may be used instead of a separate pair of bells, the chimes brought into play as desired by adjusting the mounting of the same upon the supporting member 20.

60 By arranging the slots in the bars at varying distances from the striker, the mount of the bells of various sizes is permitted.

In Figs. 5 and 6, I have shown a striker 65 28 mounted on the clock 9 adapted for recip-

rocal movement so as to strike a xylophone bar or other sounding bar 29 mounted on the supporting member 20', the supporting member 20' in this case being channel shaped and provided with side flanges 30 and 30' to 70 prevent the bar 29 from removal therefrom, a suitable layer of felt or the like being interposed between the bar and the upper surface of the supporting member 20' to separate the metallic members, it being desirable 75 that the legs 12 and 12' and the supporting members 20 and 20' be made from metal. However, this is also optional with the one constructing the device, as other suitable material may be discovered which would 80 serve the purpose equally well. The striker 28 reciprocating will be brought into contact with the bar 29 so as to produce the sound to effect the alarm. It is apparent that the bar 29 may be of any desired length 85 and may be removed at will and replaced by another of different length, so as to give off a different tone of sound.

While I have illustrated and described the preferred form of structure, I do not wish 90 to limit myself to the precise form of structure shown, but desire to avail myself of such variations and modifications as come within the scope of the appended claims.

Having thus described my invention, what 95 I claim as new and desire to secure by Letters Patent is:

1. An alarm clock of the class described comprising a pair of arcuate legs adapted for mounting on the periphery of the alarm 100 clock; an alarm supporting member connecting said legs adjacent their free ends, said supporting member being provided with a plurality of elongated slots formed therein; a plurality of alarm members; a 105 striking member on said clock adapted for striking said alarm members when operating; a supporting pin projecting from each of said alarm members and adapted for projecting through one of said slots and means 110 for locking said alarm members in fixed relative position to said supporting member.

2. An alarm clock of the class described comprising a pair of legs; a supporting member connecting said legs adjacent their 115 free end and provided with a plurality of elongated slots; a plurality of alarm members; a striking member on said clock adapted for striking said alarm members when operating; a supporting pin projecting from each of said alarm members and adapted for projecting through one of said slots and means for locking said alarm members in fixed relative position to said supporting member.

3. An alarm clock of the class described comprising legs; an alarm striking member on said clock; an alarm supporting member; alarm members mounted on said supporting member in co-operative relation to said 130

striking member; and means for adjusting said alarm members relatively to said striking member.

4. An alarm clock of the class described comprising a clock supporting means; an alarm supporting means associated with said clock supporting means; an alarm striking

member on said clock and a plurality of alarm members mounted on said alarm supporting means adjustable relatively to said alarm striking means.

In testimony whereof, I have signed the foregoing specification.

HERMAN MAIBAUER.
